GLOVE RACK

Guy Vrignaud, Grenoble, France, assignor to Allibert
Exploitation Societe Anonyme, Puteaux, France

Filed Nov. 6, 1974, Ser. No. 521,488

Claims priority, application France May 6, 1974

Term of patent 14 years

Int. Cl. D6—04; D23—02

U.S. Cl. D6—116

FIG 1

FIG 2

FIG 4

FIG 3

FIG 5

FIG 6

FIG. 1 is a perspective view of a glove rack showing my new design;

FIG. 2 is a front elevational view thereof;

FIG. 3 is a rear elevational view thereof;

FIG. 4 is an end elevational view thereof, the opposite end elevational view being identical;

FIG. 5 is a top plan view thereof; and

FIG. 6 is a bottom plan view thereof.

I claim:

The ornamental design for a glove rack, as shown and described.
